Patented Mar. 30, 1915.

Fig. 1.

UNITED STATES PATENT OFFICE.

GEORGE VRANAY, OF BRADDOCK, PENNSYLVANIA.

COMBINED RAIL TIE, CHAIR, AND JOINT.

1,133,593.

Specification of Letters Patent. Patented Mar. 30, 1915.

Application filed June 10, 1914. Serial No. 344,238.

To all whom it may concern:

Be it known that I, GEORGE VRANAY, a subject of the King of Hungary, residing at Braddock, in the county of Allegheny and 5 State of Pennsylvania, have invented certain new and useful Improvements in Combined Rail Ties, Chairs, and Joints, of which the following is a specification, reference being had therein to the accompanying 10 drawing.

This invention relates to a combined rail tie, chair and joint, and has for its object to provide a device of such class, in a manner as hereinafter set forth, for supporting 15 a pair of track rails upon a road bed as well as providing means for connecting the opposing ends of a pair of track rails together without the employment of nuts or bolts, at the same time providing for the necessary 20 contraction and expansion due to climatic influences.

Further objects of the invention are to provide a combined rail tie, chair and joint, which is comparatively simple in its construction and arrangement, strong, durable, 25 efficient and convenient in its use, readily set up, and comparatively inexpensive to manufacture.

With the foregoing and other objects in 30 view, the invention consists of the novel construction, combination and arrangement of parts as hereinafter more specifically described and illustrated in the accompanying drawings, wherein is shown an embodiment 35 of the invention, but it is to be understood that changes, variations and modifications can be resorted to which come within the scope of the claims hereunto appended.

In the drawings wherein like reference 40 characters denote corresponding parts throughout the several views:—Figure 1 is a cross sectional view of a combined tie, chair and joint in accordance with this invention, and Fig. 2 is a top plan broken 45 away.

Referring to the drawings in detail, 3 denotes a tie which is formed out of any suitable material, preferably concrete and has its top face formed with a depressed portion 50 providing a seat 4 and a pair of shoulders 5 and 6. The seat 4, between its center and the shoulder 6, has a longitudinally extending pocket 7 and said seat 4 at the shoulder 5 has a longitudinally extending pocket 8. 55 Mounted upon the seat 4 is a chair plate 9, having a pair of depending flanges 10 and

11, the former extending into the pocket 7, and the latter into the pocket 8. One side of the chair plate 9 is of greater thickness than the other side as indicated at 12, and 60 projects above the top of the tie 3.

The reference characters 13 and 14 denote a pair of track rails and each includes a head 15, web 16 and base 17, the latter being seated upon the plate 9 and having one edge 65 flushed with the flange 10.

Formed integral with the enlarged side of the plate 9 is a base flange 18 of a fish plate 19. The latter extends from the flange 18 to the heads 15 of the rails 13 and 14. 70 The base flange 18 of the fish plate 19 is mounted upon one side of the bases 17 of the rails 13 and 14. The fish plate 19 is positioned at one side of the rails 13 and 14, and positioned upon the other side of 75 said rail is a fish plate 20, having a base flange 21, which engages the bases 17 of the rails 13 and 14.

Formed integral with the base flange 21 and mounted upon the seat 4, and abutting 80 against the bases 17 of the rails 13, and further abutting against the plate 9 is a locking member 22, which is fixedly secured in position through the medium of a series of holdfast devices mounted in the tie 3, and 85 engaging in the locking member 22. The holdfast devices prevent longitudinal movement of the locking member 22 while the latter prevents lateral movement of the track rails, as well as the chair plate. 90

What I claim is:—

1. The combination with a tie body having a depression in the top face thereof, to form a seat and side shoulders, said seat being provided with a pair of longitudinal 95 pockets, one of which is contiguous with a side shoulder; of a chair plate provided at its ends with depending flanges snugly fitting in said pockets and abutting one of said side shoulders, an extension on one side 100 of the chair plate adapted to overlap the base flanges of a rail and forming a fish plate for one side thereof, a locking plate between the other side shoulder and said chair plate, an additional extension on said 105 locking plate adapted to overlap the opposite base flanges of a rail and also forming a fish plate therefor, and fastening means between said locking plate and the adjacent side shoulder of the tie body. 110

2. The combination with a tie body having a depression in the top face thereof, to

form a seat and side shoulders, said seat being provided with a pair of longitudinal pockets, one of which is contiguous with a side shoulder; of a chair plate provided at 5 its ends with depending flanges snugly fitting in said pockets and abutting one of said side shoulders, an extension on one side of the chair plate adapted to overlap the base flanges of a rail and forming a fish plate there-
10 for one side thereof, a locking plate between the other side shoulder and said chair plate, an additional extension on said locking plate adapted to overlap the opposite base flanges of a rail and also forming a fish plate there-

for, the outer side edge of the locking plate 15 being provided with threaded sockets and set screws inserted through the adjacent side shoulder of the tie body and engaged with said threaded sockets to secure said locking plate and the other parts of the device in 20 position.

In testimony whereof I affix my signature in the presence of two witnesses.

GEORGE VRANAY.

Witnesses:

MAX H. SROLOVITZ,
L. DUNN.
